(57) **CLAIM**

The ornamental design for a pram, as shown and described.

DESCRIPTION

FIG. 1 is a front perspective view of a pram, showing my new design;

FIG. 2 is a left elevation view of the pram, with the right elevation view being a mirror image of the left elevation view;

FIG. 3 is a front elevation view of the pram; and,

FIG. 4 is a rear elevation view of the pram.

The broken lines shown in the figures represent environment and form no part of the claimed design.

1 Claim, 4 Drawing Sheets(56)
